UNITED STATES PATENT OFFICE.

CHRISTIAN ZOLLINGER, OF FORT WAYNE, INDIANA.

COMBINATION-LOCK FOR ELECTRIC SWITCHES.

1,252,530.

Specification of Letters Patent.

Patented Jan. 8, 1918.

Application filed December 2, 1915. Serial No. 64,685.

To all whom it may concern:

Be it known that I, CHRISTIAN ZOLLINGER, a citizen of the United States of America, and resident of Fort Wayne, in the county 5 of Allen and State of Indiana, have invented certain new and useful Improvements in Combination-Locks for Electric Switches, of which the following is a specification.

This invention relates to improvements in 10 combination locks for electric switches and is especially intended for controlling electric circuits employed in connection with the power apparatus of automobiles, although the invention is applicable to various other 15 devices. The object of the invention is to provide a lock that may be operated without the use of a key, which will control an electrical switch, the especial feature being a combination lock with but few parts and 20 affording a great number of adjustments.

The object of the invention is accomplished by the construction illustrated in the accompanying drawings in which:—

Figure 1 is a vertical longitudinal section 25 of the device;

Fig. 2 is a front end view of Fig. 1;

Fig. 3 is a detail view of the lock-disk;

Fig. 4 is a perspective view of one of the 30 commutation bars;

Fig. 5 is a view showing one end of the barrel containing a portion of the apparatus; and

Fig. 6 is a view showing the inner end of the switch that is controlled by the locking 35 mechanism, the switch stem being shown in section.

Similar characters of reference indicate corresponding parts throughout the several views and referring now to the same:

1 is a barrel having a head (2) at one end thereof, and (3) is a shield secured to the head of the barrel, the shield having a flange (4) that serves as a means for mounting the device. A shell (5) is secured in the end 45 of the barrel opposite the head and has secured through its outer wall electrical terminal screws (6), suitably insulated therefrom and positioned diametrically opposite each other. A switch-stem (7) extends 50 through the front of the shield (3), the head of the barrel (2) and the back of the shell (5) and is adapted to be rotated therein. Upon the front end of the stem is fixed a knob (8) by means of which the 55 same may be turned, and also upon the stem, adjacent the inner side of the head of the

barrel is fixed a lock-disk (9) having in its periphery a series of notches (10). The knob and lock-disk, being fixed on the stem at points thereon at respectively opposite 60 faces of the head of the shield and the head of the barrel, prevents the stem from having longitudinal movement. A switch-bar (11) is mounted upon the stem (7) and is longitudinally movable thereupon but is prevented 65 from turning relative to the stem by means of a key (12). The outer ends of the switch-bar (11) has oppositely disposed flaring cheeks (13) and are adapted to engage with corresponding contact springs (14) 70 which have electrical contact with and are secured in place by the screws (6) respectively. A coil spring (15) bears against the hub of the switch-bar (11) at one end, and at its opposite end against a pin (16) that 75 projects from the stem (7), so that the switch-bar tends to bear against the contact springs (14) when the stem is so turned as to bring the switch-bar into connection therewith. A series of bars (17) extend 80 through the head of the shield and also through the head of the barrel, the same being made preferably square in cross-section. The openings (18) in the head (2) are made 85 rectangular so that the bars may be shifted longitudinally therein but are prevented from being turned rotatively. In each of the bars, at points selectively prearranged are made notches (19) suitably proportioned to span the outer edge of the lock-disk when 90 alined therewith, and the notches (10) in the disk (9) are so proportioned and located as to receive the edges of the respective bars. In the outermost edge of each of the bars 95 (17) is made a series of V-shaped notches (20) adapted to be engaged by corresponding pawls (21) that are pivoted between projecting ears (22) on the head (2) of the barrel, there being a spring (23) in connection with each of the pawls bearing against 100 the adjacent wall of the shield to press the pawl into contact with the corresponding bar. The engaging end of each pawl is shaped to fit in the V-shaped notches of the corresponding bar so that the latter may be 105 moved longitudinally in either direction, the intention being that the pawls shall tend to detain the bars in various adjusted positions but not prevent their being moved to other positions. Each of the bars has fixed to its 110 outer end a knob (24) by means of which the same is manipulated, and each bar may

have also marked thereupon a series of graduation marks (25).

In using the invention, electrical connection is made between the terminal screws 5 in series with the ignition circuit of the power apparatus of an automobile, or other electrical circuit, and the bars are manipulated by moving them longitudinally so that the notches of each bar register with the 10 lock-disk (9) so as to admit of the turning movement of the latter. The switch-stem (7) is then turned by manipulating the knob (8) to a point where the switch-bar (11) connects with the contact springs (14), 15 thus closing the switch and completing the electrical circuit (not shown) that leads to the electrical igniting system of the power apparatus. While the apparatus is thus adjusted the switch may be manipulated off 20 or on as desired, and in the event of it being desired to lock the switch in open position, the switch is then turned off by turning the knob (8) that the notches register respectively with the bars. The bars are then 25 shifted lengthwise indiscriminately so that their notches are out of alinement with the disk, thus the disk is prevented from being turned one way or the other and the switch-stem is therefore held from being turned 30 and the switch-bar is accordingly held in open position. Before the switch may again be thrown into closed position it is necessary to manipulate the several bars in order to bring them into positions respectively so 35 that their notches will again register with the disk so that the latter may be rotated as the switch-stem is turned. The graduation marks on the several bars serve as a guide to the operator in adjusting them to their 40 respective positions so that their notches (19) in each will register with the disk. It is the intention to locate the notches (19) on the various bars at different points thereon so that a different adjustment of 45 each bar is required in order to bring the notch therein in registry with the disk, so that a particular adjustment of each bar is required in order to have all of the notches alined in the plane of the disk.

50 It is essential that the notches in the disk

be so located that when they are respectively in alinement with the corresponding bars so that the latter may be shifted, that the switch-bar will be in open position. Or, that the stem may only be turned to bring 55 the switch-bar into closed position when all the notches of the various bars register with the disk.

What I claim is:—

1. In a device of the class described, an 60 actuating stem, a lock-disk fixed upon the stem and having a series of peripheral notches, a series of slidable bars arranged in parallel relation with the stem and adapted to engage respectively in the correspond- 65 ing notches and prevent the lock-disk from turning, each bar having made therein a recess suitably proportioned to admit of the lock-disk being turned when the bars are so adjusted that their respective recesses all 70 register with the lock-disk, and a series of pawls correspondingly arranged with the respective lock-bars and being adapted to bear against the same.

2. In a device of the class described, a 75 barrel having a head at one end thereof, a hollow shield in connection with one end of the barrel, an operating stem extending through the shield and head of the barrel having a lock-disk fixed thereon, the latter 80 having a series of peripheral notches, a series of slidable bars extending through the shield and head in parallel relation with the stem and being adapted to engage respec- 85 tively in the notches of the lock-disk, each 90 bar having a recess therein adapted to admit of the rotating movement of the lock-disk when brought into alinement therewith, and a series of spring-pressed pawls within the shield adapted to bear respectively 90 against the bars and hold the latter in the various positions to which they may be adjusted.

In testimony whereof I affix my signature in presence of two witnesses.

CHRISTIAN ZOLLINGER.
